Amos Shepard,
By James Shepard, Atty.

UNITED STATES PATENT OFFICE.

AMOS SHEPARD, OF PLANTSVILLE, ASSIGNOR TO THE PECK, STOW & WILCOX COMPANY, OF SOUTHBURG, CONNECTICUT.

TINSMITH'S BEADING-MACHINE.

SPECIFICATION forming part of Letters Patent No. 377,470, dated February 7, 1888.

Application filed December 12, 1887. Serial No. 257,605. (No model.)

To all whom it may concern:

Be it known that I, AMOS SHEPARD, a citizen of the United States, residing at Plantsville, in the county of Hartford and State of Connecticut, have invented certain new and useful Improvements in Tinsmiths' Beading-Machines, of which the following is a specification.

My invention relates to improvements in tinsmiths' beading-machines; and the object of my invention is to provide an attachable and detachable rest for supporting a tube of considerable length when it is desired to bead the same.

In the accompanying drawings, Figure 1 is a side elevation of a known beading-machine with my improvement attached thereto. Fig. 2 is a longitudinal section of my attachable and detachable rest, together with the lower beading-roller and a portion of the lower shaft. Fig. 3 shows, respectively, a sectional view and side elevation of the nut for securing the beading-roller in place when the rest is removed. Fig. 4 is a view corresponding to Fig. 2, showing a modified construction; and Fig. 5 represents a sectional and side view of the cap-screw for holding the beading-roller when the rest is removed.

The beading-machine represented in Fig. 1 is made in accordance with my Letters Patent No. 356,897, February 1, 1887; but my present improvement is applicable to other known forms of beading-machines.

A designates the lower beading-roller, fitted upon the shaft end, with its end abutting against the collar *a* on said shaft in the usual manner. At the front end of the roller the projecting shaft end *b*, Fig. 2, is screw-threaded, to receive the ordinary holding-nut, Fig. 3, for securing the roller in place. When this nut is upon the shaft end, the machine is in its ordinary condition, and may be used in the ordinary manner. For short work it will be most convenient to use the machine in this condition.

When it is desired to form a bead upon a tube or vessel that projects some distance beyond the point to be beaded, it is desirable to

have an internal rest for supporting the work. This I accomplish by removing the ordinary nut, Fig. 3, and screwing upon the shaft and up against the end of the beading-roller the rest-rod *B*, said rod having, in the form shown in Figs. 1 and 2, a flange, *c*, the periphery of which is angular, for the application of a wrench. At the end of said rod is a central bore, which is threaded to match the thread on the end *b* of the shaft. The side face of the flange is squared and presses against the outer end of the roller *A*, and thereby holds the roller in place, the same as does the nut, Fig. 3. On this rest-rod *B*, I form the rest *C*, which is bored out to fit the rest-rod, upon which it slides, and is provided with a set-screw, *d*, for holding it in its adjusted position upon the rod. A cylinder or vessel may be supported on this rest while forming the bead, and it will revolve with the beading-rollers without being driven by hand.

The construction shown in Figs. 4 and 5 is substantially the same as that before described, except that the threads are inverted—that is to say, the threaded interior is formed on the shaft end, while the exteriorly-threaded portion *e* is formed on the guide-rod *B*. A flange, *f*, having an angular periphery for the application of a wrench, has one side squared up to form the shoulder for bearing against the outer end of the roller.

When it is desired to use the machine without the rest, the rest-rod is unscrewed and the cap-screw, Fig. 5, in the modification shown in Fig. 4, or a nut, Fig. 3, in the construction shown in Figs. 1 and 2, is substituted for the rest-rod, to hold the roller in place. In both constructions the lower shaft is provided with a threaded end, while the rest-rod has a screw-thread which is fitted to the threaded end of said lower shaft.

By this construction the rest is not only conveniently attached and detached, but it is attached in such manner as to run true, and to practically form a continuation of the lower shaft, and it may be made of any desired length; or, if required, two or more rest-rods

of different lengths may be furnished for one machine.

I claim as my invention—

In a beading-machine, the combination of
5 the lower shaft, having a threaded end, and
roller, with the rest C and rest-rod B, having
a holding-shoulder and a screw-thread, and

adapted to be attached and detached from said
shaft and roller, substantially as described,
and for the purpose specified.

AMOS SHEPARD.
